UNITED STATES PATENT OFFICE.

WILLIAM G. SEELEY, OF BROOKLINE, MASSACHUSETTS.

ELECTRICAL HOSE SIGNALING APPARATUS.

SPECIFICATION forming part of Letters Patent No. 749,633, dated January 12, 1904.

Application filed May 25, 1903. Serial No. 158,621. (No model.)

To all whom it may concern:

Be it known that I, WILLIAM G. SEELEY, a citizen of the United States, and a resident of Brookline, in the county of Norfolk and State 5 of Massachusetts, have invented new and useful Improvements in Electrical Hose Signaling Apparatus, of which the following is a specification.

My invention relates to the electrical transmission of signals from the nozzle of a fire-hose to the engine, pump, or other source from which water is supplied to the hose. According to a common construction of such signaling systems the body portions of the hose-couplings are included in and made to form a part of one branch of the electrical circuit, the other branch being formed either by the ground itself, which is objectionable for many reasons, or by conductors which are completely insulated from the respective lengths of hose which carry them and from the couplings as well and are electrically connected at the couplings by means of suitable insulated contact-pieces. These contact-pieces as usually constructed heretofore have been so arranged, however, that the necessary contact between them is not made unless the parts of the hose-coupling are firmly and immovably secured together, said contact being dependent on the elasticity of springs of one sort or another, which are compressed when the contact is made, and it has been found that such arrangements are objectionable, partly because spring-contacts are apt to lose their elasticity, and therefore their operativeness, after a certain amount of use, but chiefly because when water under pressure is turned into a hose the hose tends to straighten under the pressure of the water, as is well known, and by this straightening the hose is often made to rotate a greater or less portion of a turn, with the result that the screw-couplings commonly employed become slightly unscrewed, thus breaking the contact between the contact-terminals above referred to and rendering the circuit inoperative.

My invention is intended to remedy the defects above described by providing for a screw-coupled hose a signaling-circuit which cannot be broken by any accidental unscrewing of

the parts of the coupling, such as is liable to occur in practice, and will have no tendency to lose its operativeness with use or wear. To this end I utilize the metallic threads of the engaging portions of the couplings as contact- 55 terminals for both branches of the signaling-circuit, each screw-threaded portion being formed in two parts which are suitably insulated from each other and each of these parts being electrically connected with one branch 60 of the circuit in such manner that when the half-couplings are screwed together each separate part of the screw-threads on one half-coupling engages a corresponding portion of the screw-threads on the other half-coupling 65 and makes electrical contact therewith.

In the accompanying drawings, Figure 1 is a longitudinal section through the adjacent ends of two lengths of hose connected by a screw-coupling and provided with my improvements in their preferred form. Fig. 2 is a fragmentary view showing a portion of what is shown in Fig. 1 on an enlarged scale. Fig. 3 is a detail sectional view, also on an enlarged scale, showing a movable contact- 75 piece employed in my construction; and Fig. 4 is a plan view, partly in section, of the parts shown in Fig. 3 as viewed from the left of said figure.

Referring to the drawings, 2 and 3 represent the two halves of a screw-coupling attached to corresponding lengths of hose, the half-coupling 3 having a swiveled collar 4, which is provided internally with screw-threads adapted to engage the externally- 85 screw-threaded end of the half-coupling 2 in accordance with the usual and well-known construction. The screw-threaded portion of each half-coupling, however, is divided into two parts or sections, which are insulated 90 from each other. Thus referring to the half-coupling 2, it is shown as having its end portion 5 externally reduced in diameter and screw-threaded to receive an internally-screw-threaded ring 6, which is best made of 95 hard rubber. The outer end of this ring 6 is also externally reduced in diameter and screw-threaded to receive a metallic ring 7, which is thus insulated from the body portion of the half-coupling. The external screw-threads 100

on this half-coupling, which are engaged by the screw-threads on the collar 4, are formed partly in the metallic ring 7, partly in the insulating-ring 6, and partly in the body portion 5 of the half-coupling itself, the metallic screw-threads being thus divided into two sections or portions, which are insulated from each other. In a similar manner the internal screw-threads on the swiveled collar 4 are formed partly in a metallic ring 8, partly in an insulating-ring 9, and partly in another metallic ring 10, the ring 10 being screwed into an annular enlargement formed in the ring 9, the ring 9 being screwed into the collar 4, and the ring 8 being screwed directly into the outer end of said collar in such manner that the metallic rings 8 and 10 are separated by the ring 9, and thereby insulated from each other. These rings are so positioned and proportioned that when the half-couplings are screwed together the ring 8 is in contact with the body portion of the half-coupling 2, the insulating-rings 6 and 9 are in contact with each other, and the metallic 15 rings 7 and 10 are in contact with each other, and a sufficient number of threads are formed on each of these rings to permit a partial unscrewing of the half-couplings without disengaging the metallic screw-threads carried 20 by either half-coupling from the corresponding metallic screw-threads on the other half-coupling with which they are intended to engage. The desired contact will evidently be secured, even though the metallic sections 25 on one of the half-couplings do not form complete rings. The engaging metallic screw-threaded sections are respectively connected to insulated circuit-wires 11 and 12, with which each length of hose is provided and which form 30 parts of the signaling-circuit leading to the hose-nozzle. These wires are preferably embedded in the substance of the hose itself, so that they will not be located within the water-way and extend along the hose in sinuous 35 lines to provide for the lengthening of the hose, which occurs when it is filled with water under pressure, this being a usual construction. Each wire 11 is attached at its ends directly to the half-couplings to which it leads, 40 as at 13, this branch of the circuit being, therefore, completed by the engagement of the internal threads on the ring 8 with the threads formed on the body portion of the half-coupling 2 when the half-couplings are screwed together. The wire 11 for the half-coupling 3 is not shown in the drawings, being located 45 on the opposite side of the hose from the wire 12; but it will be understood that it is attached to the half-coupling 3 in the same manner in which the corresponding wire 11 is attached to the half-coupling 2, as shown in Fig. 1. The wire 12 corresponding to the half-coupling 2 is passed at its end through an insulating-bushing 14, inserted in a hole drilled 50 lengthwise through the internal annular abut- 55 ment 15, forming a part of the half-coupling, thence through the insulating-ring 6, and thence through or into the metallic ring 7, to which its bared end is soldered. The wire 12 corresponding to the half-coupling 3 is electrically connected with the metallic ring 10; but since this ring 10 moves with the swiveled collar which carries it it is necessary to provide a movable contact between this wire 12 and said ring 10, and to this end I prefer to 60 insert an insulating-bushing 16 in a hole drilled lengthwise through the annular abutment 17 of the half-coupling 3, into which bushing the end of the wire 12 passes. A metallic tip 18 leads from the end of the wire 12 through the bushing 16, and a metallic spring 19 is secured to the end of said tip, said spring being formed to extend around a portion of the circumference of the half-coupling 3 and to bear against the interior of the ring 10 in 65 all positions of the latter, a sufficient space being provided at one end of the internal screw-threads formed on said ring to receive said spring. Inasmuch as the collar 4 has no movement toward or away from the half-coupling 3, there is no tendency at any time to vary the compression of the spring contact-piece 19 or to cause it and the ring 10 to separate. 70

Each of the circuit-wires 12 is preferably formed near its attached ends into a coil 20, extending completely around the corresponding half-coupling and located in an annular groove 21, formed therein, the object of this arrangement being to provide for the accidental separation of a length of hose and its half-coupling without breaking the circuit-wire, and to the same end the circuit-wires 11 are provided near their attached end with a number of loops 22, both of these arrangements being old in the art. 75

Each length of hose is secured at its end to the corresponding half-coupling in any suitable manner, as by means of a ring 23, which is expanded against the interior of the hose, and thus clamps the latter against the corrugated inner wall of the half-coupling. 80

24 and 25 represent packing-rings located between the ends of the hose and the annular abutments of the respective half-couplings, and 26 represents a packing-ring located between the meeting ends of the half-couplings, this packing-ring being recessed at one side sufficiently to receive the contact-piece 19. 85

As thus constructed when the half-couplings are screwed together one branch of the signaling-circuit leads through the wires 11, the body portions of the half-couplings themselves, the collar 4, and the ring 8, and the other branch leads through the wires 12, ring 6, ring 10, and contact-piece 19, and it will be seen that this construction not only provides for the partial rotation of the collar 4 without breaking either branch of the signaling-circuit, but also leaves the waterway with- 90

in the hose and coupling wholly unobstructed by anything which might interfere with or be damaged by the flow of water. The contact-surfaces between the half-couplings are kept bright and clean by the frictional rubbing of the threads due to the coupling and uncoupling of the lengths of hose, and the points of contact between the contact-piece 19 and the ring 10 are also kept bright in a similar manner by the rotation of said ring 10 with respect to the half-couplings when the collar 4 is turned.

What I claim is—

1. The combination of two half-couplings adapted to be screwed together, an insulating device separating the engaging screw-threaded portion of each half-coupling into two sections each adapted to engage the corresponding section on the other half-coupling, and circuit-wires electrically connected with said sections respectively.

2. The combination of two half-couplings adapted to be screwed together, the engaging screw-threaded portion of each half-coupling comprising two sections one of which is insulated from the body portion of the half-coupling, circuit-wires connected respectively with the insulated section of each half-coupling, and circuit-wires attached directly to the respective half-couplings.

3. The combination of a half-coupling provided with external screw-threads, an insulating-ring dividing said threads into two sections, circuit-wires connected with said sections respectively, a coöperating half-coupling having an internally-screw-threaded, swivelled collar, the screw-threads on said swivelled collar being also divided into two sections by an insulating-ring, a contact-piece carried by the body portion of the latter half-coupling

and arranged in contact with one of said sections, and circuit-wires connected with said contact-piece and with the other of said sections respectively.

4. The combination of a half-coupling provided with an insulating-ring 6 and a metallic ring 7 carried by said insulating-ring 6, said half-coupling and ring 7 being provided with external screw-threads, circuit-wires leading to said half-coupling and ring 7 respectively, 45 a coöperating half-coupling provided with a metallic ring 8, an insulating-ring 9 and a metallic ring 10 carried by said insulating-ring 9, said rings 8 and 10 being internally screw-threaded to coöperate with the screw-threads 55 on the other half-coupling, and circuit-wires leading to said rings 8 and 10 respectively.

5. The combination of a half-coupling 2 provided with an insulating-ring 6 and a metallic ring 7 carried by said insulating-ring 6, said 60 half-coupling and ring 7 being externally screw-threaded, circuit-wires connected respectively with the half-coupling 2 and to the ring 7 a coöperating half-coupling 3 provided with a swiveled collar 4, a metallic ring 8 carried by said collar, an insulating-ring 9 also carried by said collar, a metallic ring 10 carried by said insulating-ring, said rings 8 and 10 being internally screw-threaded, an insulated metallic contact-piece 19 carried by the 65 half-coupling 3 and arranged in contact with the ring 10, and circuit-wires connected respectively with the half-coupling 3 and the contact-piece 19.

In testimony whereof I have hereunto subscribed my name this 16th day of May, 1903.

WILLIAM G. SEELEY.
